UNITED STATES PATENT OFFICE.

WILHELM LANGGUTH, OF ESSLINGEN, GERMANY, ASSIGNOR, BY MESNE ASSIGNMENTS, TO UNITED STATES ENVELOPE COMPANY, OF SPRINGFIELD, MASSACHUSETTS, A CORPORATION OF MAINE.

PROCESS OF MAKING WINDOW-ENVELOPS.

1,341,807.

Specification of Letters Patent.

Patented June 1, 1920.

Application filed December 9, 1911, Serial No. 664,894. Renewed November 18, 1918. Serial No. 263,101.

To all whom it may concern:

Be it known that I, WILHELM LANGGUTH, a subject of the German Emperor, residing at Esslingen, in the Kingdom of Wurtemberg, Empire of Germany, have invented certain new and useful Improvements in Processes of Making Window-Envelops, of which the following is a specification.

This invention relates to the manufacture 10 of "window" envelops, money bags, with transparent portions and so forth. The so-called "window" envelops have been hitherto constructed by taking the unfolded envelop blank, which is the cut paper which 15 possesses the stamped out form of the unfolded cover or the like, and covering it on one side in the well known manner with a coating of varnish to the size of the required windows or transparency, after 20 which the blanks having been sufficiently dried are folded with the varnished side inward so that the outer side thereof is mat in accordance with the requirements of the post office, and is capable of being written 25 upon.

The process which forms the present invention is distinguished from that hitherto in use for the manufacture of these envelop blanks essentially by the feature that in it 30 the already finished envelops are provided with transparent parts or windows, the outer side whereof is mat in accordance with the regulations and this in such a manner that the coating of varnish which has 35 been applied does not transfer itself to the rear side of the envelop.

The object in view is attainable by the use of a machine, preferably of a rotary type, which operates upon completed envelops. This machine applies to the front or address side of each envelop a coating of varnish, of the required size for the transparent patch, such varnish being preferably composed of resinous oils such as oil of 40 turpentine, and being of a balsamic consistency at a temperature of about 20° Réaumur, to the end that there may be no tendency of the same to penetrate the paper to such an extent as to cause the adherence of 45 the reverse surface of said front side to the back of the envelop. To the coating of varnish thus applied to the address side of the envelop is imparted the quality of being mat, or capable of being written upon, by

the application thereto of a specially prepared paste which in no way impairs the transparency of the patch. The paste is composed of chalk, varnish and drier, for example, but may be composed of other suitable substances.

The new process possesses moreover the special advantage over that already known in that the cost of production of these envelops is very greatly reduced, because in consequence of the less space required by 65 the separate folded envelop as compared with the extended unfolded envelop blanks a very much greater daily output can be attained and the very troublesome sticking together of the blanks by reason of the coating is practically prevented. Moreover the transparent portions can be applied in any desired form, size and position upon the envelops.

By the process set forth, not envelops 75 alone but also money bags, wrappings for rolls of coin and such like may be provided with transparent portions. When desired, as for instance, in the case of money bags, the rendering mat can be dispensed with.

For the carrying out of the process the machine with rotary motion may be employed, which is illustrated in the accompanying drawing.

Figure 1 is a perspective view of the machine,

Fig. 2 shows in side view the parts necessary for the production of the windows,

Fig. 3 and Fig. 4 are respectively a plan view and a section of the window-envelop, 90 made in accordance with the new process,

Fig. 5 and Fig. 6 show the same views of an envelop made with the old process.

In accordance with the present invention, the finished envelops (Figs. 3 and 4), held 95 in position on press cylinder *a* by clips, are at the time they pass cylinder *b*, which carries the varnish cliché, provided on their front side with a coating of varnish, corresponding in size and shape to the window 100 *c*, while simultaneously the impression of the window frame *d* and of the name of the firm etc. is made.

Cylinder *b* or rather its varnish cliché receives the varnish by means of the rubber 105 cylinder *e* and this in turn is supplied with the varnish by the steel cylinder *f* which dips in reservoir *g*, containing the varnish,

The envelops, upon leaving the machine, are finished if the previously mentioned matting substance has been immediately added to the varnish in receptacle *g*, if this however has not been done and if a subsequent matting of the coat of varnish is required by means of the paste mentioned above, then the envelops are fed to an additional machine, which may be of any kind of rapid printing press and which applies the paste. For the proper regulation of the distances between cylinders *e* and *f*, both sides of the machine frame *h* are provided with a single arm lever *i*, adapted to rotate on an eccentric box *k* on the axis of cylinder *f* and which forms the bearing of axis *l* of cylinder *e*.

By rotating box *k* by means of the hand-wheel *m*, the distance between the cylinders *e*, *f* can be regulated, and in accordance the supply of varnish can be lessened or increased. Each lever *i* is tightly pressed by a spring *n* to a setscrew *o*, and an adjustment of this screw *o* will regulate the pressure of cylinder *e* on cylinder *b* or on the varnish cliché. Press cylinder *a* revolves loosely on an eccentric axis *p*, which carries on its extreme end a handlelever *q*. In consequence, a rotation of handlelever *q* raises cylinder *a* from cylinder *b*, and at the same time cylinder *e* is somewhat removed from cylinder *b* by means of guiderod *r*. As shown by Figs. 5 and 6, the window envelops were formerly constructed in such a manner that the unfolded envelop windows were on their inner side provided with a layer of varnish *c*, and the window frame *d* was printed on the outside. This illustration clearly shows the great advantages of the new process over the old.

The varnish used for transparentizing may be some resinous oil, such as oil of turpentine, having a balsamic consistency.

The above described process requires two

working operations: firstly the application of the varnish and secondly the making mat by aid of a paste. In order to be able to varnish and mat the envelops in a single operation, so that the entire production is greatly simplified and may be more effectively carried out, it is advisable that the finished envelops be treated upon a machine capable of rotary motion and constructed specially for this purpose with automatic motion by the application of a varnish to which a matting substance, such as wax, spermaceti, or the like has been added, giving the preparation the property of drying to a "mat" surface. This operation of varnishing can be effected at the same time as the gumming of the edge and stamping of the firm name so that the envelops are immediately available for use when dried and correspond in every respect to the postal requirements.

What I claim and desire to secure by Letters Patent is:

1. The herein described process which consists in forming an envelop or a like article and then applying to a portion of the outer surface of the article a varnish having a balsamic consistency at a temperature of about 20° Réaumur and to which varnish has been added a matting substance such as wax, spermaceti or the like.

2. The herein described process which consists in applying to a portion of the outer surface of the envelop or like article, a varnish adapted to render said portion transparent, to which varnish has been added a substance adapted to render mat said transparent portion.

In testimony whereof I affix my signature in presence of two witnesses.

WILHELM LANGGUTH.
